ABSTRACT OF THE DISCLOSURE

An apparatus for flushing cisterns which has a valve controlling the entry of water into the cistern and a water discharge fitting mounted on the floor of the cistern. A submersible float of general U-shaped configuration having hollow side members, an open-topped compartment communication with the interiors of the side members, a flexible conduit means interconnecting the open-topped compartment to the water discharge fitting and manual control means for submerging the float to effect flushing.

The present invention relates to apparatus for flushing cisterns.

The object of the invention is to provide apparatus as referred to above which is of simple construction, positive in action and easy to operate.

The invention consists in apparatus for flushing cisterns comprising, a valve controlling the entry of water into the cistern, a water discharge fitting mounted on the floor of the cistern, a submersible float, flexible conduit means interconnecting the float and water discharge fitting, and manually controlled means for submerging the float to effect flushing.

In the accompanying drawings:

FIGURE 1 is a perspective view of a flushing cistern according to the present invention,

FIGURE 2 is a perspective view, similar to FIGURE 1, but showing a modified form thereof, and

FIGURE 3 is a perspective view of a cover having a volume control mechanism.

In carrying the invention into effect according to one convenient mode, by way of example, the apparatus comprises a cistern 10 for holding the flushing water with a discharge fitting 11 mounted on the floor 12 thereof and a known type of float-operated valve 13 mounted in an end wall 14 of the cistern 10 controlling the entry of the water. Preferably, the water enters the cistern 10 through a conventional silencer tube 15 screwed into the body of the valve 13.

A float 16 of generally U-shaped configuration has hollow side members 17 interconnected at one end by a hollow member 18 and a wall 19 spaced from the member 18. A base 20 extending between the side members 17 and the member 18 and wall 19 forms an open-topped compartment 21.

The compartment 21 communicates with the interior of the hollow side members 17 and the latter each have an aperture 22 in their upper surface at the end remote from the chamber 21.

A strut 23 having a ledge 24 interconnects the side members 17 at the end adjacent their respective apertures 22 and a further strut 25, positioned between the strut 23 and the chamber 21, is hingedly connected by means of an arm 26 to the inlet valve 13 so that with the float 16 resting on the floor 12 of the cistern 10 the valve 13 is open, permitting the entry of water into the cistern 10, whilst as the float 16 rises the valve 13 is gradually closed until a predetermined level of water is reached in the cistern 10 when the valve 13 is closed.

2

An aperture in the wall 19 of the compartment 21 is connected by means of a flexible pipe 27 to the water discharge fitting 11 in the floor 12 of the cistern 10.

The cover or top 28 of the cistern 10 has a downwardly extending cylindrical boss 29 in which is slidably mounted an operating button 30 to which is rigidly connected a pushrod 31 having a float-engaging portion 32. A spring 33 urges the button 30 and associated pushrod 31 upwardly, whilst a projection 34 on the boss 29 engages a slot 35 in the button 30 to retain the latter in position.

In operation, when a flush is required, the button 30 is depressed which causes the portion 32 of the pushrod 31 to engage the ledge 24 on the strut 23 and so lowers that end of the float 16 just enough to submerge it so that the water flows into the interior of the hollow side members 17 through the apertures 22 and the float sinks to the bottom of the cistern 10. With the float in this position the water in the cistern passes into the float through the apertures 22 and compartment 21 and then, from the compartment 21, through the flexible pipe 27 and out through the discharge fitting 11.

As is usual, the rate of flow of the outgoing water is far greater than the rate of flow of the water entering the cistern 10 through the inlet valve 13 and, therefore, the level in the cistern is rapidly lowered. When the level reaches the top of the float, the volume of water inside the float rapidly decreases, the buoyancy of the float is re-established and it rises to float on the surface of the water once more, hence preventing further discharge through the fitting 11.

The valve 13 is now open and water enters the cistern through the silencer tube 15. The float 16 and its associated arm 26 rise with the level of the water until the required level is reached, when the valve 13 is again closed by the action of the arm 26.

In the modified construction shown in FIG. 2, components similar to those shown in FIG. 1 have been given similar reference numerals and the following description only deals with the differences in construction and operation of the two embodiments.

In FIG. 2 the arm 26 is pivotally connected to a bracket 36 mounted on the end wall 14 of the cistern 10 and the valve 13 is controlled by a conventional ball float 37 and lever 38 arrangement.

In operation of the construction shown in FIG. 2, when the button 30 is depressed, the float 16 is submerged and the water in the cistern 10 passes out into the discharge fitting 11 through the hollow float 16 as described above. The consequent lowering of the level of the water in the cistern 10 causes the ball float 37 to drop, which in turn opens the valve 13 and allows water to enter the cistern through the silencer tube.

The float 16 and ball float 37 rise together until the required water level is reached, when the valve 13 is again closed by the action of the lever 38 associated with the ball float 37.

The present invention may also be applied to what is known as a multi-flush cistern in which a predetermined amount of the flushing water contained in the cistern is used upon operation of the control. In this construction, a further button 39 and pushrod 41 as shown in FIG. 3 is mounted on the cover 28. The button 39 is a tight sliding fit in a boss 40 and preferably bears indicia showing the volume of water which will be discharged from the cistern for any given position of the button 39. The pushrod 41 is cranked through 90° and the lower end thereof is positioned beneath the float 16 so that if, for example, only half the water in the cistern is to be used, the lower end of the pushrod 41 is positioned by the button 39 to the requisite level to prevent

the float 16 falling to the bottom of the cistern 10 after it has been submerged.

It will be readily appreciated that changes may be made in the construction of the apparatus without effecting its basic principle of operation and some of these changes are detailed below.

Preferably, the flexible pipe 27 is of corrugated form moulded from a synthetic resinous material, but if desired, a rigid tube having a flexible coupling at one, or each, end may be used.

If required, the float 16 may have additional buoyancy by providing an air-tight compartment. Furthermore, the base of the float 16 is shaped so that it falls from both ends towards the aperture in the wall 19 which minimizes the amount of water retained in the float 16 when it is not submerged.

It will be readily appreciated that the float must have a density slightly greater than the density of water to ensure it will drop to the bottom of the cistern. This can be achieved either by making the float from a material having the required density, or by weighting the float. Furthermore, the top of the float may be completely open.

I claim:

1. Apparatus for flushing cisterns comprising a valve controlling the entry of water into the cistern, a water discharge fitting mounted on the floor of the cistern, a submergeable float of generally U-shaped configuration having hollow side members interconnected at one end by a further hollow member forming one side of an open-topped compartment which communicates with the interior of said side members, flexible conduit means interconnecting said open-topped compartment and water discharge fitting, and manually controlled means for submerging the float to effect flushing.

2. Apparatus for flushing cisterns as claimed in claim 1, wherein the submergeable float is pivotally connected to said valve.

3. Apparatus for flushing cisterns as claimed in claim 1, wherein the submergeable float is pivotally connected to an end wall of said cistern and a ball float has an associated lever pivotally connected to said valve.

4. Apparatus for flushing cisterns as claimed in claim 1, wherein an aperture is provided in the upper surface of each side member at the end remote from said compartment.

5. Apparatus for flushing cisterns as claimed in claim 1, wherein a strut interconnecting said side members is adapted to be engaged by said manually controlled means.

10 6. Apparatus for flushing cisterns as claimed in claim 1, wherein said manually operated means comprises a button slidably mounted in the cover of said cistern with a pushrod which is adapted to engage said submergeable float rigidly connected to said button.

15 7. Apparatus for flushing cisterns as claimed in claim 1, wherein means are provided for controlling the volume of water discharge from said cistern.

8. Apparatus for flushing cisterns as claimed in claim 7, wherein said means comprises a button and associated push-rod slidably mounted in the cover of said cistern, the push-rod being cranked at its lower end and positioned beneath said submergeable float to prevent, if necessary, the float falling to the bottom of the cistern after it has been submerged.
